UNITED STATES PATENT OFFICE.

HENRY M. GABEL, OF CINCINNATI, OHIO, AND THOMAS E. KEARNS, OF NEW KENSINGTON, PENNSYLVANIA.

RED-LEAD FURNACE.

SPECIFICATION forming part of Letters Patent No. 689,868, dated December 31, 1901.

Application filed September 16, 1901. Serial No. 75,493. (No model.)

To all whom it may concern:

Be it known that we, HENRY M. GABEL, residing at Cincinnati, Hamilton county, Ohio, (post-office address No. 3320 Reading road, 5 Avondale, Cincinnati, Ohio,) and THOMAS E. KEARNS, residing at New Kensington, Westmoreland county, Pennsylvania, (post-office address New Kensington, Pennsylvania,) citizens of the United States, have invented certain new and useful Improvements in Red-Lead or Litharge Furnaces, of which the following is a specification.

This invention, pertaining to improvements in furnaces for the coloring of casing in the 15 production of red lead or litharge, will be readily understood from the following description, taken in connection with the accompanying drawings, in which—

Figure 1 is a side elevation, Fig. 2 a vertical longitudinal section, Fig. 3 an end view, and Fig. 4 a vertical transverse section, of our improved furnace.

In the drawings, 1 indicates a pair of shafts disposed horizontally and parallel with each 25 other in suitable bearings near the base of the general structure; 2, flanged carrying-wheels fast on the ends of these shafts; 3, a shaft at right angles for the shafts 1; 4, bevel-gearing connecting shaft 3 with one or, if desired, both of shafts 1, shaft 3 to be driven 30 from any suitable source of power; 5, a metallic cylinder lined with refractory material and disposed with its horizontal axis over and between the two shafts 1; 6, metallic hoops 35 upon the cylinder 5, the same engaging the flanged wheels 2 in such manner that the turning of shaft 3 results in the rotation of the cylinder; 7, a charging-door in the periphery of the cylinder; 8, a discharging-door 40 disposed in the end of the cylinder and as far outward radially as the inner diameter of the cylinder will permit; 9, a large circular opening in that end of the cylinder farthest from discharging-door 8; 10, a gas-discharge outlet 45 disposed axially in the opposite end of the cylinder; 11, a flue having connection with outlet 10; 12, a fuel-furnace disposed near that end of the cylinder opposite flue 11; 13, its grate; 14, its fire-door; 15, its ash-door; 50 16, a boss projecting from furnace 12 into the opening 9 of the cylinder; 17, a passage-way

through this boss whereby the combustion-chamber of furnace 12 is placed in communication with the interior of the cylinder; 18, annular shields within the cylinder around 55 openings 10 and 17; 19, a flue in the wall of furnace 12; 20, a segmental series of ports in the cylinder end of boss 16, these ports communicating with flue 19; 21, a blower; 22, a connection from the blower to flue 19; 23, a 60 pair of wheeled axles on furnace 12, with their axes at right angles to the axis of cylinder 5, and 24 a track for the wheels of the furnace, the same extending rearwardly from the cylinder. 65

In using this apparatus the dross or casing is charged into the cylinder 5 through door 7 till the cylinder is about one-sixth full, the apparatus being preferably of a capacity to make such charge equal about two tons. The 70 cylinder is then rotated at, say, about one revolution per minute for about ten hours, or more if needed. The hot products of combustion from furnace 12 pass into the cylinder and act upon the tumbling dross or casing 75 therein and finally escape through flue 11. At the same time air under pressure and heated by passage through the hot walls of the furnace enters the cylinder and acts upon the dross or casing therein, the heat and air 80 ultimately bringing about the coloring desired for the red lead or litharge. When the process is complete, then the blast is shut off and the charge withdrawn through opening 8. After each discharging or at such less frequent intervals as may render it desirable the 85 furnace 12 is wheeled away from the cylinder, thus leaving the opening 9 free and open, so that proper tools may be employed in thoroughly clearing the interior of the cylinder. 90 Such operations through the opening 9 will in some cases be found desirable during the regular process of discharging the cylinder, as the position of the opening gives fair access to the entire inwall of the cylinder. In some cases 95 such thorough clearing of the cylinder as calls for the employment of opening 9 as a cleaning-opening may be only occasional.

Shields 18 serve to keep the tumbling dross or casing out of openings 10 and 17 while the 100 cylinder is revolving.

This apparatus may be used singly or in

battery, and in practice should be provided with overhead track for charging-cars and with receiving-conveyer for the withdrawn charges.

5 We claim as our invention—

1. In a red-lead or litharge furnace, the combination, substantially as set forth, of a horizontally-disposed refractory-lined rotary cylinder having axial openings in each of its ends 10 and having charging and discharging openings, mechanism for supporting and rotating said cylinder, a discharge-flue connection at one of said axial openings in the cylinder, a fuel-furnace, a fixed boss projecting 15 from said fuel-furnace and into the other axial opening in the cylinder and having a passage through it connecting with said fuel-furnace, and having also a hot-blast air-passage to said cylinder, wheels upon said fuel-furnace with their axes at right angles to the axis of said cylinder, and a track for said wheels.
2. In a red-lead or litharge furnace, the combination, substantially as set forth, of a hori-

zontally-disposed refractory-lined rotary cylinder having axial openings in each of its ends 25 and having charging and discharging openings, mechanism for supporting and rotating said cylinder, a discharge-flue connection at one of said axial openings in the cylinder, a fuel-furnace, a fixed boss projecting 30 from said fuel-furnace and into the other axial opening in the cylinder and having a passage through it connecting with said fuel-furnace, and having also a hot-blast air-passage to said cylinder, wheels upon said 35 fuel-furnace with their axes at right angles to the axis of said cylinder, and a track for said wheels.

HENRY M. GABEL.
